UNITED STATES PATENT OFFICE.

WALTER P. MURPHY, OF CHICAGO, ILLINOIS.

CAR-ROOF.

1,343,785.

Specification of Letters Patent. Patented June 15, 1920.

Application filed January 29, 1919. Serial No. 273,823.

To all whom it may concern:

Be it known that I, WALTER P. MURPHY, a citizen of the United States, residing at Chicago, county of Cook, and State of Illinois, have invented certain new and useful Improvements in Car-Roofs, of which the following is a description.

In the drawing:

Figure 1 is an enlarged detail transverse sectional view of a car roof taken on the line 1—1 Fig. 2.

Fig. 2 is a detail top plan view of a car roof embodying my invention.

Fig. 3 is an enlarged detail sectional view 15 on the line —3—3— Fig. 2.

Fig. 4 is an enlarged detail sectional view showing the flexible joint between roof sheet and the eaves flashing.

Fig. 5 is a detailed plan view of a car 20 roof illustrating another embodiment of my invention.

The object of my invention is to provide for securing the roof sheets in operative position on the car and free to move about to 25 a limited extent.

The invention consists in positioning the roof sheets and holding them down upon the roof substructure by means at the marginal edges of the roof sheets and leave the 30 sheets free to move about within certain limitations.

A further object of my invention is to so mount the roof sheets that they may move as if on a pivot at their ridge ends.

35 A further object of my invention is to provide a construction at the ridge whereby the roof sheets may pivot on their ridge corners.

Further objects and particulars of the invention will appear from the following description of the roof construction shown in 40 the accompanying drawings.

The reference numeral 1 designates a suitable roof sheathing of a car.

The roof plates or sheets 2 are connected 45 at their eaves end to a flashing 3, the joint between the flashing and the roof sheets being a loose flexible joint as shown in detail in Fig. 4.

The side marginal edges of the roof sheets 50 are provided with upwardly standing rebent flanges 4 which interlock with a seam cap 5. Between the marginal flanges 4 of the roof sheets I position a mullion 6 which is suitably secured to the roof sheathing, 55 there being a space between the side marginal flanges 4 and the mullion whereby the

sheets are free to move with respect to said mullion.

The ridge end of the roof plate or sheet is provided with an open re-bend 6^a which 60 overlies the upper face of the roof plate and is adapted to receive a filled strip 7 which is suitably secured therein and extends approximately the width of the sheet or plate. As will be seen from the drawing the wood 65 filler or strip extends beyond the free edge of the bend 6, the object of which will be hereinafter stated.

A ridge cap 8 is provided with downwardly extending side flanges 9 which 70 terminate at the bottom in an outwardly extending flange 10 which flange 10 overlies the roof sheet or plate 2. It will be seen that the ridge ends of the roof plates, on opposite sides of the ridge, are normally spaced 75 from each other under the ridge cap, while wood filler strip 7, carried by the roof plates is in contact with the side flanges 9 of the ridge cap. The wood filler strip 7 extends beyond the free edge of the bend 6 of the 80 plate 2 so that the edge of the bend 6 is prevented from coming into contact with the side flanges 9 of the ridge cap, thereby eliminating the possibilities of said edge cutting through the ridge cap. This is of importance 85 because the roof sheets or plates are prevented from moving bodily toward the eaves of the car by reason of the filler strip 7 abutting the side flange of the ridge cap, besides which the roof sheets or plates, 90 being free at its marginal edges to move to compensate for service movement of the car, without injury to the sheets or plates, and in such movements said plates frequently pivot on its ridge corners said corners being 95 fulcrumed on the side flanges of the ridge cap and as the wood filler strip 7 contacts with the flange of the ridge cap, there is no danger of the ridge cap becoming worn or cut by such pivotal action of the roof plate. 100

The running board saddle 11 has a recess 12 of a size to receive the ridge cap as shown in Fig. 1, the side walls of the recess approximately fitting against the outer face of the side flanges 9 of the ridge cap, where- 105 the said side flanges are sustained against stress in a direction toward the eaves of the car.

All joints between the parts at the eaves, roofs seams, and ridge are weather proof. 110

The wood filler strip 7 constitutes a rigidifying element across the ridge end of the

roof sheet or plate which stiffens and reinforces the ridge end and prevents the ridge end of the plate from buckling or being distorted by stresses incident to the service movements of the car and roof so that there is very little, if any, likelihood of the roof plate becoming jammed at the ridge, therefore the joint between the ridge cap and the roof plate is always maintained normal, whereby the slipping action at said joint is always free.

In Fig. 5 the construction is substantially like that heretofore described, the only exception being that the filler strip 7^a is convex on its eaves edge whereby the roof plates rocks on said convex edge instead of pivoting on its corners as described in connection in Figs. 1, 2, and 4. In this construction it will be seen that there is a running board saddle 11 positioned opposite the apex of the convex edge of the filler strip 7^a.

From the above it will be seen that in the construction shown in Figs. 1, 2 and 4, the roof plates are movably mounted on the substructure and spaced apart at the ridge and at the side marginal edges, and have a free loose flexible connection with the flashing at the eaves, and are free to pivot at their ridge corners to compensate for service movement; while in Fig. 5 the construction is the same with the exception that the filler strip is convex on its eaves side, whereby the sheet or roof plates pivot at a point between their side marginal edges at their ridge ends.

The abutment of the filler strip on the ridge end of the sheet or plates is the sole means of restraining bodily movement of the roof plates toward the eaves of the car.

Matter shown but not claimed herein is claimed in my application, filed January 29, 1919, Serial No. 273,824.

What I claim is:—

45 1. In a car, a roof including a sheathing, a ridge cap, and metal roof sheets mounted on said sheathing and free to pivot at their ridge corners on the ridge cap.

50 2. In a car a roof including roof plates, a ridge cap, an abutment on the ridge end of the roof plates mounted within said cap and free to move therein to accommodate the service movements of the roof plates whereby said roof plates may move in an arc in the plane of the roof.

55 3. In a car, a roof including roof plates, a ridge cap, an abutment on the ridge end of the roof plates freely mounted within said cap but limited in movement toward the eaves, whereby said cap and abutment hold the plates free to pivotal movement in the plane of the roof but restrained in movement toward the eaves.

60 4. In a car, a roof including roof plates, a loose weather proof connection between the

side marginal edges of adjacent plates, a ridge cap, an abutment on the ridge end of the roof plates freely mounted within said cap, whereby the plates are free to move pivotally and otherwise in the plane of the roof but are restrained in bodily movement toward the eaves.

65 5. In a car, a roof including plates, and a ridge cap, a pivotal connection between the ridge end of the plates and said cap; whereby the body of plates is free from connection with a roof substructure between said cap and its eaves end and whereby the eaves end and the ridge end and the intermediate body portion of the plates are free to move as if on a pivot without buckling.

70 6. In a car, a roof including plates, and a ridge cap, a rigidifying element on the ridge end of the plates freely confined under said cap and constituting an abutment to restrain the plates against movement toward the eaves, but leaving the plates free to move in the plane of the roof as if on a pivot.

75 7. In a car, a roof including plates, a ridge cap, and an abutment on the ridge end of the plates confined under said cap to restrain the plates against movement toward the eaves, but leaving the plates free to move in the plane of the roof as if on a pivot.

80 8. In a car, a roof including plates free at the eaves and ridge ends and throughout its body portion from any rigid connection with the roof substructure, and a loose connection between the ridge cap and ridge end of the plates to restrain the plates from movement toward the eaves.

85 9. In a car, a roof comprising a sheathing, metal plates pivotally mounted on and at all points lying close to the upper surface of said sheathing, connections between the plates permitting movement thereof in the plane of the roof, a ridge cap, and a loose connection between the ridge end of the plates and said cap constituting the sole means for restraining movement of the plates toward the eaves.

90 10. A car roof, comprising a supporting sheathing, metal roof plates loosely mounted thereon and free from any connection therewith and spaced apart along the ridge and along the marginal side edges, mullions extending from the ridge to the eaves of the roof and positioned between but spaced from the side marginal edges of the roof plates, a seam cap over the mullion and side marginal edges of the roof plates forming a weather proof joint between adjacent plates, the side marginal edges of the plates having play between the mullions and the seam cap, a ridge cap, an abutment on the ridge end of the plates freely mounted with the ridge cap and restraining the movement of the plates only toward the eaves.

95 11. In a car, a roof including a sheathing,

- metal roof plates each extending from a point approximately near the ridge to approximately near the eaves, a ridge cap, a loose rocking connection between the ridge cap and the ridge end of the roof plates.
12. In a car, a roof including a sheathing, metal roof plates each extending from a point approximately near the ridge to a point back from the eaves, a ridge cap and a loose rocking connection between the ridge cap and the ridge end of the roof plates.
13. In a car, a roof including metal roof plates each extending transversely of the car from a point approximately near the ridge, a ridge cap, a loosely rocking connection between the ridge cap and the ridge end portion of the plates constituting the sole means of restraining the movement of the plates toward the eaves.
14. In a car, a roof including metal roof plates each extending transversely of the car from a point approximately near the ridge, an eaves flashing, a free loose flexible joint between said flashing and the eaves end of the plates whereby the eaves end of the plates are free to move toward the eaves relatively to the flashing, a ridge cap, a loose rocking connection between the ridge end of the plates and the ridge cap, said connection constituting the sole means of limiting the movement of the roof plates toward the eaves.
15. In a car roof the combination with movably supported roof plates, of a ridge cap and a rocking connection between said plates and cap whereby said plates may move bodily without buckling or imposing strain upon them or the cap.
16. In a car, a roof including a sheathing, roof plates bodily movably mounted thereon, an open return bend at the ridge end of the roof plates spaced from the upper face of said plates, a filler secured in said open bend and extending approximately the width of each plate, a ridge cap having downwardly extending side flanges against which the filler abuts to limit the movement of the plates toward the eaves, the ridge end of the plates with their fillers being otherwise free to move within said ridge cap.
17. In a car, a roof including a sheathing, roof plates bodily movably mounted on said sheathing, an open return bend at the ridge end of the plates overlying but spaced from the upper face of the plate, a filler secured in said open return bend and extending approximately the width of the plate, a ridge cap having downwardly extending side flanges against which the filler is adapted to abut to limit the bodily movement of the plate toward the eaves, the ridge end of the plate and filler being otherwise free to move within said ridge cap, and flanges extending outwardly from the bottom of the side flanges of the cap substantially in the plane of the upper face of the roof plates.
18. In a car, a roof including roof plates bodily movably mounted on the car, an open return bend at the ridge end of the plates overlying but spaced from the upper face of the plate, a filler secured in said open return bend, and extending approximately the width of the plate, a ridge cap having downwardly extending side flanges against which the filler is adapted to abut to limit the bodily movement of the plate toward the eaves of the car, the ridge end of said plate and its filler being otherwise free to move within said ridge cap, flanges extending outwardly from the bottom of the side flanges of the cap substantially in the plane of the upper face of the plate, and a running board saddle fitted over said ridge cap and approximately engaging the side flanges of the cap thereby constituting an abutment for said side flanges to prevent the deflection of said side flanges by service movements of the plate and its filler.
19. In a car, a roof including a sheathing, metal plates unattached to said sheathing and bodily movably mounted thereon, an open return bend at the ridge end of the plate, spaced from and overlying the upper face of the plate, a filler secured within said bend and having a convex outer longitudinal face, a ridge cap overlying said bend and filler and having downwardly disposed side flanges against which the corner face of said filler is adapted to abut.
20. In a car, a roof including a sheathing, metal plates unattached to said sheathing and bodily movably mounted thereon, an open return bend at the ridge end of the plate spaced from and overlying the upper face of the plate, the edge of said bend being convex, a filler secured between said bend and the upper face of the plate, and having a convex outer longitudinal face, a ridge cap overlying said filler and bend and having downwardly disposed side flanges against which the convex face of the filler abuts, whereby there is a rocking connection between the plate and cap; which connection is the sole means of limiting the bodily movement of the plate toward the eaves.
21. In a car, a roof plate having an open return bend at its ridge end overlying and spaced from the upper face of the plate and a filler secured in said bend constituting a transverse rigidifying member for the plate.
- In testimony whereof I affix my signature in the presence of a witness.
- WALTER P. MURPHY.
- Witness:
- BENNETT P. JONES.
